UNITED STATES PATENT OFFICE

101,397

DESIGN FOR A FIRE LIGHTER

George H. Reimer, Fulton, Ill., assignor to Patent Novelty Company, Fulton, Ill., a corporation of Illinois

Application June 4, 1936, Serial No. 63,021

Term of patent 3½ years

To all whom it may concern:

Be it known that I, George H. Reimer, a citizen of the United States, and resident of Fulton, in the county of Whiteside and State of Illinois, have invented a new, original, and ornamental Design for a Fire Lighter, of which the following is a specification, reference being had to the accompanying drawing, forming a part thereof:

Fig. 1 is a perspective of a fire lighter showing my new design.

Fig. 2 is a perspective view of the bowl portion of the fire lighter shown in Fig. 1.

Fig. 3 is a perspective view of the handle portion of the fire lighter shown in Fig. 1.

The dominant feature of my design is shown in solid black lines which consists of a symmetrically formed cup with a slightly flared upper edge, and with the loop portion of the wire handle contributing to the symmetrical and ornamental rim effect of the cup when the handle and cup are combined.

I claim:

The ornamental design for a fire lighter, as shown and described.

GEORGE H. REIMER.
